Attorney

UNITED STATES PATENT OFFICE.

ARTHUR R. BAKER, OF INDIANAPOLIS, INDIANA, ASSIGNOR TO IRA T. SWARTZ, OF INDIANAPOLIS, INDIANA.

FASTENING CLAMP.

Application filed June 9, 1926. Serial No. 114,851.

My said invention relates to a clamp adapted for fastening a closure plate over the fuel inlet of a furnace when applying a liquid fuel burner or the like thereto.

5 It is an object of the invention to provide means which may be easily applied and removed for converting an ordinary coal or wood burning furnace into an oil burning furnace. It is necessary to provide a closure 10 for the fuel inlet which is imperforate or tight fitting and it is an object of my invention to provide a clamp which may be attached to the lugs or sections of the hinge usually formed integral with the body of 15 the furnace and with the catch for the conventional furnace door latch all as will be hereinafter more particularly described and claimed.

It has been necessary in applying such 20 closure plates to the conventional furnace to set the plates in the fuel opening and fasten them in position by means of furnace cement or the like whereupon it is necessary to permit the same to dry before the oil burner 25 nozzle could be mounted on the same. However, with my structure it is possible to entirely complete the installation of the device without loss of time. It is also customary with some mechanics to drill openings 30 through the furnace around the fuel opening to supply bolts therethrough for holding the plates in position. This has been found objectionable since such construction impairs the operation of the furnace if it is desired 35 to be reused for consumption of coal or similar fuel.

Referring to the accompanying drawings which are made a part hereof and on which similar reference characters indicate similar 40 parts,

Figure 1 is a fragmentary front elevation of a furnace illustrating the application of my invention,

Figure 2, a section on line 2—2 of Figure 1, and

Figure 3, a section on line 3—3 of Figure 1.

In the drawings reference character 10 indicates a furnace having a fuel inlet 11 with perforated hinge lugs or bosses 12 and a 50 catch 13, all of conventional construction.

In the usual furnace a fire box door is provided which is pivoted on the bosses or lugs 12 and is provided with a latch which rides into a notch 14 of the catch or upstanding boss 13.

A closure plate 15 is provided with perforations 16 corresponding to the location of the three lugs or bosses 12 and 13 and in order to clamp this closure plate in position I provide a hollow casing 17 having a cylindrical bottom which tapers to a reduced eccentric top 18 spaced therefrom but with one point of each circumference being in substantially the same vertical plane while the diametrically opposed points in circumferences are joined by an inclined surface. The reduced top of said casing is provided with an opening through which a screw is inserted for engagement with the perforations in the bosses of the furnace. Said screw comprises a rod threaded at its outer end for engagement by a wing-nut 21 and having its opposite end 20 bent at substantially right angles to its body 19. In applying the device to a furnace it is only necessary to drill a hole in the boss or lug 13 whereupon the entire closure for the furnace door may be applied without the use of tools.

If desirable the furnace may be restored to its original condition whereupon coal or other fuel may be used and the furnace will not have been injured by the change.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

1. The combination with a furnace having a fuel inlet with door engaging lugs, of a removable closure plate for said fuel inlet, hollow casings concealing said lugs, and bolts extending through said lugs and hollow casings for securing them together, substantially as set forth.

2. The combination with a furnace having

lugs extending outwardly therefrom, of a plate secured over said lugs and having perforations through which the lugs extend, a hollow casing fitted over each lug, a bolt extending through said hollow casing and said lug for fastening the same together, and a wing nut on the end of said bolt for adjust-

ably securing the lug and bolt together, substantially as set forth.

In witness whereof, I have hereunto set 10 my hand at Washington, District of Columbia, this 28th day of May, A. D. nineteen hundred and twenty-six.

ARTHUR R. BAKER.
